CLAIM

The ornamental design for a microwave antenna cover, as shown and described.

DESCRIPTION

FIG. 1 is a top plan view of a microwave antenna cover, showing our new design, the bottom being a mirror image; FIG. 2 is a front elevational view thereof, the rear being a mirror image;

FIG. 3 is a right side elevational view thereof; FIG. 4 is a left side elevational view thereof; and, FIG. 5 is a top right isometric view thereof.

The details shown in broken lines in FIGS. 1, 2, 4 and 5 are shown for illustrative purposes only and form no part of the claimed design.
